UNITED STATES PATENT OFFICE.

MOSBY MONTAGUE, OF CHRISTIANSBURG, VIRGINIA, ASSIGNOR TO WILMONT VENTILATING COMPANY, INC., OF ROANOKE, VIRGINIA.

AIR-CIRCULATING DEVICE.

1,197,144.

Specification of Letters Patent.

Patented Sept. 5, 1916.

Application filed November 8, 1915. Serial No. 60,361.

To all whom it may concern:

Be it known that I, MOSBY MONTAGUE, a citizen of the United States, residing at Christiansburg, in the county of Montgomery and State of Virginia, have invented certain new and useful Improvements in Air-Circulating Devices; and I do declare the following to be a full, clear, and exact description of the invention, such as will 10 enable others skilled in the art to which it appertains to make and use the same.

My invention relates to improvements in air circulating devices and has for its object to provide an extremely simple yet 15 highly efficient contrivance of this class capable, by the use of a single rotary fan, of supplying fresh air into a building, drawing the foul air therefrom, and discharging such foul air into the atmosphere on the 20 exterior of the building.

With this general object in view, the invention resides in certain novel features of construction and in unique combinations of parts to be hereinafter fully described and 25 claimed, the descriptive matter being supplemented by the accompanying drawings which constitute a part of this application, and in which:

Figure 1 is a diagrammatic longitudinal 30 section of a theater showing the improved device applied; Fig. 2 is a horizontal sectional view as seen on the plane of the line 2-2 of Fig. 1; Fig. 3 is an enlarged vertical longitudinal section through the fan casing and the foul air exhaust tubes; Fig. 35 4 is a horizontal section through the casing and the fresh air supply tubes, and Figs. 5 and 6 are vertical transverse sections as seen on the planes indicated by 40 the lines 5-5 and 6-6 of Fig. 3.

In specifically describing the invention shown in the drawings above briefly described, similar characters will be placed on corresponding parts throughout the several 45 views and reference will be herein made to such parts by their respective indices. To this end, C represents a chamber to be ventilated, such chamber being considered in the present showing as a moving picture theater or the like in which the usual 50 seats S are provided, such seats being supported upon the floor F which inclines upwardly and rearwardly as is common in theaters, and numerous other types of assembly halls.

Disposed at an appropriate point on the exterior of the building, is a casing 1 here shown as formed of a cylindrical section 2 and a conical section 3 connected therewith at its enlarged end, the section 2 being equipped with an end wall 4 having a central aperture 5 which serves as a fresh air inlet, while the contracted end of the section 3 is connected in any preferred manner to one or more upright pipes 6 which constitute supplemental air inlets. Two pipes 6 are shown as leading through one wall of the building to points a short distance below the ceiling thereof and above the floor. The curved side of the casing section 2 is 60 provided with a plurality of main fresh air outlets 7 from which pipes 8 lead into the building at an appropriate level, the free ends of said pipes being equipped with air deflectors 9 capable of adjustment thereon 65 and adapted to control the currents of fresh air forced into the building by a fan yet to be described.

In addition to the features above described, the section 3 is formed with a plurality of supplemental air outlets 10 preferably having control valves 11, it being through the outlets 10 that foul air drawn from the building through the pipes 6, is 70 to be discharged. As shown in the drawings, the invention contemplates the use of a transverse partition 12 secured therein by any preferred means and preferably having its entire edge spaced from the conical wall of the section 3, portions of said edge being 75 disposed in close proximity to the foul air outlets 10 as disclosed most clearly in Fig. 4.

Operating within the casing section 2 upon a shaft 13 driven by a motor or the equivalent 14, is a rotary fan 15, the axis of such fan being disposed endwise of the casing 1. It is preferable that the central portion 16 of the fan 15 be of a diameter equal to or greater than that of the fresh air inlet 5, and that the numerous radiating blades 17 of said fan be curved transversely as shown in Fig. 4. Furthermore, the periphery of the fan should be positioned in fairly close proximity to the fresh air outlets 7 and said fan must be driven in the direction indicated by the arrows 18 in Figs. 3 and 4; that is, if the blades be pitched as shown. Obviously, however, if such blades be reversed, the direction of rotation may 100 also be reversed.

In operation, the fan 15 is rotated at a high rate of speed and is thus caused to throw air within the casing section 2 forcibly outward, with the result that such air is 5 expelled mostly through the fresh air outlets 7, but partially through the foul air outlets 10. From the outlets 7, the fresh air passes through the pipes 8 into the building, and the supply of fresh air within 10 the casing will be constantly replenished through the opening 5. The air now escaping under pressure through the openings 10 will create a strong suction through the pipes 6 and the casing section 3, the result 15 being that foul air from both the upper and lower portions of the building will be drawn through said pipes into the section 3 and will be discharged therefrom through the openings 10 into the atmosphere on the exterior of the building. The courses taken 20 by the fresh air are illustrated in Figs. 1, 2, and 4 of the drawings by full line arrows, while the directions of travel of the impure air are represented by the dotted arrows in 25 such figures.

By inspection of the drawings, it will be obvious that while the device is operating as above described, the partition 12 will readily direct some of the fresh air through 30 the openings 10, and will thus reliably prevent any noticeable amount of such air from entering the section 3. However, I have found that in some cases it is unnecessary to use this partition, since the air is generally thrown outwardly with such great 35 force as to cause it to immediately seek the numerous outlets.

From the foregoing description, taken in connection with the accompanying drawings, 40 it will be obvious that although the construction of the improved device is very simple, and comparatively inexpensive, it will be highly efficient and durable and may be inexpensively maintained.

In the drawings, certain specific details of construction have been shown for illustrative purposes, and in the preceding such details have been described, but obviously numerous changes may be resorted to within 50 the scope of the invention as claimed without sacrificing the primary advantages thereof.

I claim:

1. An air circulating device comprising a 55 main and a supplemental chamber communicating one with the other, an air inlet into the main chamber and an outlet therefrom, an air inlet into the supplemental chamber and an outlet from the latter, in combination 60 with a rotary fan in said main chamber for creating two currents of air respectively through the inlet and outlet of the main chamber and through the inlet and outlet of the supplemental chamber.

65 2. An air circulating device comprising a

casing, a partition between the ends of said casing dividing the latter into a main and a supplemental chamber, said partition being spaced from the wall of the casing to establish communication between the two chambers, main and supplemental air inlets respectively into the main and supplemental chambers, main and supplemental outlets respectively from said main and supplemental chambers, and a rotary fan in the 70 main chamber for delivering air centrifugally through the main outlet, said fan being disposed adjacent the partition and the supplemental air outlet being located near 75 said partition, whereby air from said fan 80 may likewise be discharged through said supplemental outlet.

3. An air circulating device comprising a casing having in one end a main air inlet and in its other end a supplemental air inlet, said casing also having in its side a main air outlet adjacent its first named end and a supplemental air outlet spaced toward its other end from said main outlet; in combination with a partition in the casing between 85 the main and supplemental air outlets and in close proximity to the latter, and a rotary fan in the casing having its axis disposed endwise of said casing, said fan having 90 its periphery positioned in close proximity to the main air outlet to discharge a current of air therethrough, the aforesaid partition being spaced from the curved wall 95 of the casing to also permit part of the air from the fan to be discharged through 100 the supplemental air outlet.

4. An air circulating device comprising a casing formed of a cylindrical section having a closed end and an open end, and a conical section connected at its larger end 105 with said open end of the cylindrical section, the center of the closed end of the cylindrical section being provided with a main air inlet, while the contracted end of the conical section is formed with a supplemental air inlet, the circular wall of said cylindrical section having therein a main air outlet, while the wall of the conical section is provided with a supplemental air outlet; in combination with a rotary fan mounted 110 in the cylindrical section of the casing upon an axis extending endwise of said casing and having its periphery disposed in close proximity to the main air outlet.

5. An air circulating device comprising a 115 casing formed of a cylindrical section having a closed end and an open end, and a conical section connected at its larger end with 120 said open end of the cylindrical section, the center of the closed end of the cylindrical section being provided with a main air inlet; while the contracted end of the conical section is formed with a supplemental air inlet, the circular wall of said cylindrical section 125 having therein a main air outlet, while the 130

wall of the conical section is provided with a supplemental air outlet; in combination with a rotary fan mounted in the cylindrical section of the casing upon an axis extending 5 endwise of said casing and having its periphery disposed in close proximity to the main air outlet, and a circular partition disposed at right angles to the axis of the casing and located in a plane between the main 10 and supplemental air outlets, said partition

having its edge spaced from the curved wall of the casing but positioned in close proximity to the supplemental air outlet.

In testimony whereof I have hereunto set my hand in presence of two subscribing witnesses. 15

MOSBY MONTAGUE.
